ATTORNEY

UNITED STATES PATENT OFFICE.

JOHN MAHER, OF VALLEJO, CALIFORNIA.

LUMBER SLING.

1,405,052.

Specification of Letters Patent. Patented Jan. 31, 1922.

Application filed February 2, 1921. Serial No. 441,763.

To all whom it may concern:

Be it known that I, JOHN MAHER, a citizen of the United States, residing at Vallejo, in the county of Solano and State of California, have invented new and useful Improvements in Lumber Slings, of which the following is a specification.

This invention relates to a lumber sling.

It is the principal object of the present invention to provide a lumber sling which is decidedly simple in construction and may be readily applied and removed from lumber which it is intended to be used in lifting.

The present invention contemplates the use of a long splice member having a loop in each end and slidably carrying a short splice and a hook; the short splice being also fitted with a hook by which the parts may be instantly connected or disconnected during operation.

The invention is illustrated by way of example in the accompanying drawings, in which Fig. 1 is a view in elevation showing the complete invention.

Fig. 2 is a view in end elevation showing the application of the present invention.

Referring more particularly to the drawings, 10 indicates a long splice member which comprises a cable, the ends of which 30 form loops 11 and 12. Secured upon the cable 10, at a point intermediate its looped ends, is a choke shoulder 13 adapted to limit the movement of a short splice cable 14. This cable is slidably looped on to the long 35 splice at 15. Its opposite end is fitted with a hook 16. The long splice cable is provided with a hook 17 slidably mounted thereon by means of a hook ring 18.

In application of the present invention 40 the short splice cable 14 is passed beneath a pile of lumber to be hoisted, or it may be laid flat upon the ground to receive the lumber. In any event the long cable 10 is doubled and is looped around the hook 16. 45 Loop 12 of the long cable is then carried back and is passed over the hook 17. When the members are properly adjusted the loop 11 and a portion of the long cable will extend from the center of the stack of lumber 50 and may be readily secured to a hoist as indicated in Fig. 2. When large objects are lifted the advantages of the choke shoulder 13 are evident as this prevents the looped end 12 of the cable from passing through or 55 becoming tangled with the hook 16. When the sling is applied, as shown in Fig. 2, it

will be evident that the suspension of the weight from the looped end 11 of the long cable will tend to tighten both the long and short cables, and will insure that the lumber 60 embraced thereby will be rigidly gripped during its transit. When the sling is to be removed, the cable 10 may be instantly unfastened from the hook 16 and the single length of short cable thereafter drawn from 65 beneath the lumber.

It will thus be seen that the sling here disclosed is quite simple in its construction and may be easily applied and removed from objects to be lifted, and furthermore that 70 the application of the sling to the objects is such as to insure that a positive gripping action will take place at all times that a load is suspended thereupon.

While I have shown the preferred form of 75 my invention as now known to me, I wish it understood that various changes in the construction, combination and arrangement of parts may be made by those skilled in the art without departing from the spirit of the 80 invention as claimed.

Having thus described my invention, what I claim and desire to secure by Letters Patent is—

1. A device of the character described 85 comprising a long cable having loops in its opposite ends, a short cable slidably connected to the long cable, a hook on the end of the short cable, and a hook slidably mounted on the long cable. 90

2. A lumber sling comprising a long cable having a loop at each of its ends, a stop shoulder fastened to the long cable at a point intermediate its ends, a short cable 95 slidably mounted upon the long cable between the shoulder and one of the loops, a hook slidably mounted upon the long cable between the short cable and said last named loop, and a hook secured to the end of the short cable. 100

3. A lumber sling comprising a short cable adapted to pass partially around an object to be lifted, a hook upon one end of said short cable, a loop upon the opposite end of said cable, a long cable passing through said loop of the short cable and formed at its opposite ends with loops, said long cable being adapted to pass around the opposite side of the object to be lifted and to engage the hook of the short cable, and a hook 110 slidably mounted upon the long cable and adapted to receive one of the looped ends 105

of the long cable, while the other looped end of said cable remains free to be engaged by a lifting device.

4. A lumber sling comprising a short cable adapted to pass partially around an object to be lifted, a hook upon one end of said short cable, a loop upon the opposite end of said cable, a long cable passing through said loop of the short cable and formed at its opposite ends with loops, said long cable being adapt-

ed to pass around the opposite side of the object to be lifted and to engage the hook of the short cable, a hook slidably mounted upon the long cable and adapted to receive one of the looped ends of the long cable, 15 while the other looped end of said cable remains free to be engaged by a lifting device, and a stop on the long cable adjacent the hook engaging loop thereof.

JOHN MAHER.
